(57) **CLAIM**

The ornamental design for a switch panel for a motor vehicle interior, as shown and described.

DESCRIPTION

FIG. 1 is a front view of the switch panel for a motor vehicle interior showing our new design;

FIG. 2 is a front view of an alternative embodiment thereof; and,

FIG. 3 is a front view of the design in FIG. 1, shown in a condition of use.

The broken lines illustrate portions of the switch panel for a motor vehicle interior that form no part of the claimed design. The broken lines showing a vehicle interior in FIG. 3 depict environmental structure and form no part of the claimed design. The broken lines showing symbolic break lines, indicating a continuation of already unclaimed environment, in FIG. 3, form no part of the claimed design.

1 Claim, 3 Drawing Sheets
